DESIGN FOR AN EXTINGUISHER ASH TRAY

Peter J. Swofford, Fort Worth, Tex.

Application August 9, 1943, Serial No. 110,869

Term of patent 3½ years

(Cl. D85—2)

To all whom it may concern:

Be it known that I, Peter J. Swofford, a citizen of the United States of America, residing in Fort Worth, in the county of Tarrant and State of Texas, have invented a new, original, and ornamental Design for an Extinguisher Ash Tray, of which the following is a specification, reference being had to the accompanying drawing, forming part thereof, in which:

I claim:

The ornamental design for an extinguisher ash tray, as shown.

PETER J. SWOFFORD.
